UNITED STATES PATENT OFFICE.

MERLE J. WIGHTMAN AND OSCAR URBAN, OF HARTFORD, CONNECTICUT.

ARMATURE FOR DYNAMO-ELECTRIC MACHINES.

SPECIFICATION forming part of Letters Patent No. 367,080, dated July 26, 1887.

Application filed August 19, 1886. Serial No. 211,254. (No model.)

To all whom it may concern:

Be it known that we, MERLE J. WIGHTMAN and OSCAR URBAN, citizens of the United States, residing at Hartford, in the county of 5 Hartford and State of Connecticut, have invented a new and useful Improvement in Armatures for Dynamo-Electric and other Electrical Machines, of which the following is such a full, clear, and exact description as will enable 10 any one skilled in the art to which it appertains to make and use the same.

Our invention relates to means for more effectually insulating and ventilating the coils of an armature adapted to be used with the 15 machines referred to above.

The object of the invention is primarily to keep the armature from becoming overheated, and to enable an increased air contact at points of the armature-coils, where most heat is likely 20 to be developed, by partially or wholly separating the coil-sections at the ends of the armature by air-spaces; and it has also for its object the insulating of the coils of one system from the coils of the other system in an 25 armature.

The invention consists in providing air-spaces more particularly at the ends of the armature between the coils, whereby, as the armature is rotated, the air within said spaces 30 is put in motion and displaced; and it consists, also, in details of construction whereby the foregoing results are accomplished.

In the accompanying drawings, forming part of this specification, in which the same letters 35 of reference indicate the same parts throughout—

Figure 1 is a side view of our invention, showing the coils and parts holding the same in position on the core and shaft in cross-section, and Fig. 2 is an end view of our invention.

The armature shown in the drawings is of the cylinder form, and is made up of two systems of coils, C' and C², each having two independent coils, a' b' and a² b², respectively, the coils in each system C' and C² being wound at right angles to each other, those of the second system wound upon the cylinder in the spaces between the coils of the first system. The invention is not necessarily confined to an armature having such an arrangement of coils, but

may be applied to a magneto-electric machine having any system of armature winding. We do not wish, therefore, to confine the invention to any particular form of armature winding. 55

As represented in the drawings, the coils in the system C' are wound first, covering and sealing the ends of the armature and cutting off communication between the external air 60 and the interior of the armature.

A washer or sleeve, w, of stiff insulating material—such as vulcanized fiber or hard rubber—is slipped over the shaft S, carrying the core A of the armature. A circular plate, 65 p, is placed over this washer, and has metal strips b secured thereto. These strips sustain at their outer ends a ring of wood or other insulating material. Upon this plate p and ring r are wound the coils of the outer system, C², 70 as shown in the drawings. By this construction the two systems are completely insulated from each other, and air-spaces are left at the ends of the armature between the coils, and as the armature rotates a cooling action is obtained by the circulation of the air beneath 75 the plate p. The two coils a' b' and a² b² of each system are also partially separated by air-spaces, as shown in the drawings, thus contributing to the general purposes of the invention. 80

Having now fully described our invention, we wish to have it known that we do not limit ourselves to the exact construction and arrangement shown, as the same may be varied 85 without departing from our invention; and we reserve to ourselves all changes within the scope of the same and the right in practice to make any changes within the scope of what we now desire to claim and secure by Letters 90 Patent of the United States, which is—

1. A rotating armature for an electro-magnetic or magneto-electric apparatus having coils of wire wound thereupon, separated longitudinally at the ends constituting air-spaces 95 from the axis between said coils at the ends of the armature, for the purpose described.

2. A rotary armature of the cylinder type, having coils of wire wound thereupon longitudinally, separated longitudinally at the 100 ends, making air-spaces for ventilating purposes at the ends of the armature.

3. A rotary armature for an electric apparatus, two different systems of coils wound thereupon, longitudinally separated at the ends, making air-spaces at the ends between the two systems for ventilating and insulating purposes.

4. A rotary cylindrical armature for electric apparatus, consisting of a core, a shaft carrying the same, two coils of wire wound thereupon at right angles to each other, constituting together one system of coils, another system like the first wound upon the cylindrical portion of the armature between the spaces left by the first system, and means for separating the two systems from each other at the end of the armature, for the purpose set forth.

5. In a rotary cylindrical armature for a magneto or dynamo machine, an armature-core, and a system of coils wound thereon, said coils at their crossings at the ends of the armature being separated by air-spaces.

6. The combination, in an armature, of the core A, the shaft S, carrying the same, two systems of coils, C' C², wound thereabout, the washer w, embracing the shaft between the two systems, and the plate p, resting upon the washer, for maintaining the coils C² of the second system in the position shown.

7. The combination, in an armature, of the core A, the shaft S, carrying the same, two

systems of coils, C' C², wound thereabout, the washer w, embracing the shaft between the two systems, the plate p, resting upon the washer, for maintaining the coil C² of the second system in the position shown, the insulating-ring r, and means for holding the same in position and securing it to the plate.

8. The combination, in an armature adapted to be used with a motor, dynamo, or magneto machine, of the core A, the shaft S, upon which the same is mounted, the two systems of coils C' C², wound thereabout, as described and shown, the washer w, embracing the shaft between the two systems, the circular plate p, resting upon the washer bearing the second system of coils C², the insulating-ring r, and non-magnetic strips b, for securing the latter to the plate, whereby an air-space is left for insulation and ventilation between the coils of the two systems, and the same are held firmly in place.

In testimony whereof we have hereunto set our hands and seals, this 27th day of July, 1886, in the presence of two subscribing witnesses.

MERLE J. WIGHTMAN. [L. S.]
OSCAR URBAN. [L. S.]
